UNITED STATES PATENT OFFICE.

DAVID H. DIEHL, OF PITTSBURGH, PENNSYLVANIA.

BUILDING STRUCTURE.

Application filed December 4, 1925. Serial No. 73,188.

This invention relates to improvements in building structures, and more particularly to storage garages in which automobiles may be parked or stored in congested districts.

One object of the invention is to provide a storage building so constructed that vehicles may travel under their own power from floor to floor of the building.

Another object of the invention is to provide a building of the class described with a novel arrangement of ramp drives and driveways whereby the ascending and descending streams of traffic will be independent of each other.

A further object of the invention is to provide a building of the class described in which any one of the several floors thereof may be locked off from the remainder of the floors in case of fire, while permitting the removal of the vehicles from the other floors above and below the locked off floor.

A still further object of the invention is to provide a building of the class described having the novel design, construction and arrangement of elements described in detail in the following specification and illustrated in the accompanying drawings.

In the drawings:

Figure 1 is a plan of the first floor of a building constructed in accordance with my invention.

Figure 2 is a plan of the second floor of a building constructed in accordance with my invention.

Figure 3 is a plan of the third floor of a building constructed in accordance with my invention.

Figure 4 is a sectional elevation taken on the line IV—IV of Figure 3.

Figure 5 is a sectional elevation taken on the line V—V of Figure 3.

Figure 6 is a sectional elevation taken on the line VI—VI of Figure 4.

Referring more particularly to the drawings, the numeral 2 designates the outside walls of the building which is preferably of substantially rectangular outline and may be of any desired height. The building is divided into a plurality of floors 3, 4, 5, 6, 7 and 8, although it will be understood that the number of floors will vary with the height of the building.

The first or ground floor 3 is divided into a salesroom space 9, repair shop space 10, lobby space 11, offices 12 at each side of the front of the lobby, rest-rooms 13 and passen-

ger elevator shaft 14. The elevator shaft 14 extends the full height of the building.

Driveways 15 and 16 extend from the front of the building rearwardly along each side of the lobby space 11 to ascending and descending ramp drives 17 and 18, respectively.

Stairs 19 are provided connecting each of the several floors.

The descending ramp drive 18 curves from the drive 16 and is inclined upwardly along the rear wall of the building until adjacent the second floor 4, when it curves inwardly onto said floor.

The driveway 15 parallels the one end wall of the building, and the ascending ramp drive 17 curves from said drive toward the other end of the building and is inclined upwardly along the rear wall of the building over the drive 18 and at the same degree of inclination as the ramp drive 18. However, instead of terminating at the second floor the drive 17 extends from the first floor to the third floor 5 and curves inwardly to the third floor from a point adjacent said floor.

A second descending ramp drive 20 extends from the second floor 4 upwardly to the fourth floor 6. The drive 20 communicates with the second floor at a point directly over the drive 17 and parallels said drive 17 upwardly at the same degree of inclination and communicates with the fourth floor at a point directly over the point where the drive 17 communicates with the third floor 5.

A second ascending ramp drive 21 starts from the third floor 5 at a point directly over the point where the drive 20 communicates with the second floor 4 and parallels the drive 20 upwardly at the same degree of inclination to the fifth floor 7, where it enters the floor 7 directly over the point where the drive 20 enters the fourth floor 6.

A third descending ramp drive 22 extends from the fourth floor 6 upwardly to the sixth and last floor 8. The drive 22 communicates with the fourth floor 6 at a point directly above where the drive 21 communicates with the third floor 5 and parallels the drive 21 upwardly at the same degree of inclination to a point on the sixth floor 8 directly over the point where the drive 21 communicates with the fifth floor 7.

A third ascending ramp drive 23 starts from the fifth floor 7 at a point directly over the point where the drive 22 communicates

with the fifth floor 7 and extends upwardly parallel with the drive 22 at the same degree of inclination to a point midway between the ends of the drive 22 at which 5 point the drive 23 turns or curves inwardly to enter the sixth and last floor.

The ingoing or ascending ramp drives 17, 21 and 23 are connected by driveways 24 on the third and fifth floors of the building, 10 while the descending ramp drives 18, 20 and 22 are connected by driveways 25 on the second and fourth floors. From the above it will be readily appreciated that the series 15 of ascending ramp drives 17, 21 and 23 and their connecting driveways 24 and the series of descending ramp drives 18, 21 and 22 and their connecting driveways 25 are entirely separate so that the ascending and descending lines of traffic will never conflict with 20 each other.

A fire wall 28 along the forward face of the drive 18 together with partition walls 29 and 30 along the driveway 16 entirely enclose the drive 18 from the first floor except 25 at the exit end of the driveway 16, where a fire door 31 is provided. A second fire door 31^a is provided to close the ramp drive 18 and prevent fire from the second floor reaching the first floor.

30 A fire wall 32 separates the ramp drive 17 from the second floor, except for an entrance opening 33 which permits ascending cars to enter the second floor, and this opening is closed by a fire door 34. A pair of other 35 fire doors 35 and 36 are provided to be moved across the drive 17 and prevent fire from the first floor ascending the drive to the second or third floors and to prevent fire from the third floor descending to the second or first 40 floors.

A fire wall 37 separates the ramp drive 20 from the third floor, except for an exit opening 38 which permits descending cars to enter the drive from the third floor and 45 this opening is closed by a fire door 39. A pair of other fire doors 40 and 41 are provided to be moved across the drive 20 and prevent fire from the second floor ascending the drive to the third and fourth 50 floors and to prevent fire from the fourth floor descending the drive to the third and second floors.

A fire wall 42 separates the ramp drive 21 55 from the fourth floor except for an entrance opening 43 which permits ascending cars to enter the fourth floor, and this opening is closed by a fire door 44. A pair of other fire doors 45 and 46 are provided to be moved across the drive 21 and prevent fire from 60 the third floor ascending the drive to the fourth and fifth floors and to prevent fire from the fifth floor from descending the drive to the fourth and third floors.

65 A fire wall 47 separates the ramp drive 22 from the fifth floor, except for an exit open-

ing 48 which permits descending cars to enter the drive from the fifth floor and this opening is closed by a fire door 49. A pair of other fire doors 50 and 51 are provided to be moved across the drive 22 and prevent fire from the fourth floor ascending the drive to the fifth and sixth floors and to prevent fire from the sixth floor from descending the drive to the fifth and fourth floors. 75

Fire walls 52 and 53 separate the ramp drive 23 from the sixth floor, except for an entrance opening 54 which permits ascending cars to enter the sixth floor, and this opening is closed by a fire door 55. A second 80 fire door 56 is provided to be moved across the drive 23 to prevent fire from the fifth floor ascending the drive to the sixth floor.

In case of a fire on any one of the several floors, the several fire doors may be closed 85 which control entrance and exit to that floor and the remaining floors of the building may then be emptied of cars by the use of both the ascending and descending series ramp drives. For instance, if a fire should take 90 place on the fourth floor the fire door 44 will be closed, thus closing the entrance opening 43 communicating with the drive 21, and the fire doors 50 on the drive 22 and 41 on the drive 20 will be closed to prevent 95 the fire from the fifth and third floors, respectively. Closing of the fire doors 50 and 41 will close the descending drives to cars from the fifth and sixth floors. However, the ascending drives 23 and 21 are open and may be used in an emergency to bring the cars down from the upper floors, since the drive 21 passes right by the fourth floor. 100

If on the other hand, a fire should take 105 place on the third floor the ascending series of drives only would be closed by closing the fire doors 45 and 36 and the descending drives may all be used for discharging the cars.

In Figures 2 and 3 I have shown floor 110 plans of the second and third floors, respectively. The floor plan of Figure 2 is typical of all the even numbered floors, except the top floor, regardless of the height of the building. The floor plan of Figure 3 is typical of all the uneven numbered floors, except the first floor, regardless of the height of the building. 115

The several floors are each provided with 120 a dividing wall 58 which divides the floors into two compartments, the car stalls or rooms 59 and the driveways 60 and 61 for permitting movement of the cars on the floors.

The top or sixth floor 8 will have a plan 125 the same as that of Figure 3, except that there will be no ramp entering the floor to the left of the entrance 54, thus providing room for more stalls at this point.

While I have shown and described one 130

specific embodiment of my invention, it will be understood that I do not wish to be limited thereto, since various modifications may be made without departing from the scope 5 of my invention as defined in the appended claims.

I claim:

1. A structure for housing motor vehicles comprising a plurality of horizontal floors, 10 each of said floors being on the same plane throughout, inclined drives connecting the floors, some of said drives extending from one floor to the second floor above, entrances connecting said last named drives with the 15 intermediate floors, fire walls arranged along said drives, fire doors at said entrances to the intermediate floors, and other fire doors intermediate the ends of said drives, said fire walls and fire doors being so positioned 20 that any one of the floors on which a fire may take place may be locked off from the other floors while permitting passage to the other floors.

2. A structure for housing motor vehicles 25 comprising a plurality of floors, a series of inclined drives connecting the floors for the use of incoming cars, a separate series of inclined drives connecting the floors for the use of outgoing cars, all of said drives being 30 inclined in the same direction and at substantially the same degree, said drives being alternately arranged one above the other, at least some of said drives extending from one floor to the second floor above, entrances connecting said last named drives with the 35 intermediate floors, fire walls arranged along said drives, fire doors at said entrances to the intermediate floors, and other fire doors intermediate the ends of said drives, said 40 fire walls and fire doors being so positioned that any one of the floors may be locked off from the other floors.

3. A structure for housing vehicles comprising a plurality of floors, two series of 45 drives connecting said floors, each of said series of drives being inclined in the same direction, one of said series of drives being arranged above the other, some of said drives in both of said series of drives being 50 extended from one floor to the second floor above, and entrances connecting said last named drives with the floors intermediate the ends thereof, whereby each floor of said 55 structure is served by both of said series of drives.

4. A structure for housing vehicles comprising a plurality of floors, two series of drives connecting said floors, each of said series of drives being inclined in the same direction, one of said series of drives including a lower drive extending from the first to the second floor of said structure and other drives connecting said second floor with the remaining upper floors of said structure, at least some of said last named 60 drives extending from one floor to the second floor above, said second series of drives being arranged above said first series of drives and including a lower drive extending from the first to the third floor of said structure 65 and other drives connecting said third floor with the remaining upper floors of said structure, at least some of said last named drives extending from one floor to the second floor above, and entrances connecting all of 70 said drives of both series which extend from one floor to the second floor above, with the floors intermediate the ends thereof, whereby each floor of said structure is served by both 75 of said series of drives.

5. A structure for housing vehicles comprising a plurality of superposed horizontal floors, each of said floors being on the same plane throughout, two series of ramp drives connecting said floors, each of said series of ramp drives being inclined in the same direction, one of said series of ramp drives including a lower drive extending from the first to the second floor of said structure and other drives connecting said second floor 80 with the remaining upper floors of said structure, at least some of said last named drives extending from one floor to the second floor above, said second series of drives being arranged above said first series of drives 85 and including a lower drive extending from the first to the third floor of said structure with the remaining upper floors of said structure, at least some of said last named drives extending from one floor to the second floor above, said second series of drives being arranged above said first series of drives 90 and including a lower drive extending from the first to the third floor of said structure and other drives connecting said third floor with the remaining upper floors of said structure, at least some of said last named drives extending from one floor to the second floor above, and entrances connecting all of 95 said drives of both series which extend from one floor to the second floor above, with the floors intermediate the ends thereof, whereby each floor of said structure is served by both 100 of said series of drives.

In testimony whereof, I have hereunto signed my name.

DAVID H. DIEHL.
